IRONER SHOE

Thomas J. Little, Jr., South Bend, Ind., assignor to
 Easy Washing Machine Corporation, Syracuse,
 N. Y., a corporation of Delaware

Original application March 25, 1940, Serial No.
 325,822. Divided and this application March 5,
 1941, Serial No. 381,882

10 Claims. (Cl. 219—19)

This case is a division of my copending application, Ser. No. 325,822, filed March 25, 1940; and is concerned with improvements in the construction of an ironing machine shoe.

One of the objects of my invention is to provide a simple ironing machine shoe construction that insures high efficiency of heat flow to the electric heating element to the sole plate of the shoe.

Another object of my invention is to form the sole plate and the back plate of an ironing machine shoe in such fashion that when the parts are assembled, the back plate will exert pressure over the heating element so as to force the heating element into intimate contact with the sole plate.

Still another object of my invention is to provide a simple means for locking the back plate to the sole plate.

Other objects and advantages of my invention will appear from the following specification taken in conjunction with the accompanying drawing in which:

Figure 1 is a rear elevation of an ironing machine showing the shoe of my invention.

Figure 2 is an exploded cross-sectional view of the shoe showing the separate parts thereof.

Figure 3 is a perspective view of a portion of the shoe cut away to show the cross-sectional construction.

The ironing machine shown in Figure 1 is more completely described in my copending application, Ser. No. 325,822; and for the present purpose general description will suffice. The machine comprises the base 10, the roll 11, and the shoe 12. The roll is mounted above the base by means of the fixed bracket 13. A swinging bracket 14 supports the shoe 12. The handle 15 operates mechanism, not shown, for swinging the support 14 toward and away from the roll 11. An electric motor and suitable gearing is mounted within the roll 11 for driving the same and is connected by suitable wiring to control switches, not shown, and a source of electric current, by means of the plug 16. Suitable wiring placed within the base 10 to the cord leading to the plug 16. The other ends of the wires are connected to the thermostatic switch 17 and thence to the heating element presently to be described contained within the shoe 12.

The preferred construction of the shoe is as follows:

A sole plate 20 which extends substantially the length of the ironer roll is curved laterally to

fit the roll and is provided with the retroverted edges or lips 21 and 22. An electric heating unit 25 is positioned adjacent the sole plate and in contact therewith. The heating unit 25 comprises a resistance element here shown in two sections 26 and 27, which extend longitudinally of the unit. The resistance element is secured between two sheets of mica 28 and 29, or other suitable electric insulating material that is not affected by heat. A heat insulating pad 30 is placed over the heating unit 25. The back plate 31 is formed from a sheet of metal, preferably steel, and is provided with a longitudinal marginal portion 32 adapted to slide under the lip 22 of the shoe 20 and a second longitudinal marginal portion 33 adapted to slide under the lip 21 of the shoe 20. Between the marginal portions 32 and 33 the plate 31 is bent upwardly, as at 34 and 35, to form the generally dome-shaped portion 36, which extends longitudinally of the back plate. Two longitudinal depressions 37 and 38 are formed in the dome 36. The depressions 37 and 38 are positioned so as to press the pad 30 downward over the portions of the heating unit 25 which contain the resistance elements 26 and 27, and thus press the heating unit 25 into intimate contact with the sole plate 20 when the shoe is assembled. This structure reduces the resistance of the heat flow from the sections 26 and 27 of the electric resistance unit to the sole plate 20.

I have provided a novel means for securing the back plate in position which is not only simple but also serves to hold the back plate under tension so as to continuously exert pressure on the heating element 25.

The assembly of the shoe is as follows:

The heating unit 25 is positioned longitudinally of the sole plate 20. The insulating pad 30 is then pressed over the heating unit 25. The back plate 31 is then slid endwise into position with the marginal portions 32 and 33 sprung under the lips 21 and 22 of the sole plate 20. The height of the dome-shaped portion 36 of the back plate 31 is such that in this position the portions 37 and 38 press against the insulating pad 30. Pressure is then exerted on the back plate 31 so as to force it downward with considerable force on the insulating pad 30. While still held under pressure, the rod 40 is forced down over the marginal portion 33 and under the lip 21 of the shoe 20. The rod 40 extends the full length of the shoe. The second rod 41 is forced downwardly on the marginal portion 32 of the shoe back 31 and under the lip 22 of the

shoe 20. The rod 41 likewise extends the full length of the entire shoe. The rods 40 and 41 may be further secured in place by swaging the lips 21 and 22 at intervals along the length of the lips. It is to be noted that before the rods 40 and 41 are forced into place, the marginal portions 32 and 33 contact the retroverted portions 22 and 21; and when the rods 40 and 41 are inserted, the marginal portions 32 and 33 are forced downward so as to contact the sole plate 20, thus placing the entire back plate under additional tension so as to force the depressions 37 and 38 downward against the pad 30 and thus insure that the heating element 25 is held in intimate contact with the sole plate 20.

Although I have shown a specific embodiment of my invention, it is obvious that many changes could be made in the form and parts thereof without departing from the spirit of my invention; and I, therefore, wish to be limited only by the scope of the appended claims.

I claim:

1. In an ironing machine shoe having a sole plate and an electric heating unit comprising electrically insulated resistance elements, said heating unit being placed in contact with the back of said sole plate, in combination, a heat insulating member substantially covering said heating unit, a back member, a plurality of protuberances extending inwardly of said back member and positioned over said resistance elements in such manner as to spring said back member toward said sole plate, and means for fastening said back member to said sole plate, whereby said protuberances press said insulating member against said heating unit and force said heating unit into intimate contact with said sole plate thereby providing a conductor path of low resistance for the flow of heat from said resistance element to said sole plate.

2. In an ironing machine shoe having a sole plate and an electric heating unit comprising electrically insulated resistance elements, means for pressing the effective heat producing area of said electric heating unit into intimate contact with said sole plate comprising, a heat insulating pad positioned over said heating unit, a single member constituting a back cover and pressure plate, a plurality of inwardly extending protuberances formed integrally with said member, said protuberances substantially corresponding in position and area to said resistance elements, and means for fastening said member to said sole plate.

3. In an ironing machine shoe having an electric heating element, in combination, a metallic sole plate the longitudinal edges thereof being retroverted to form U-shaped pockets, a sheet metal back plate extending substantially the length of said sole plate and shaped to form a chamber for receiving said heating element, the longitudinal edges of said back plate extending into said U-shaped pockets and wedging means adapted to be forced into said pockets over the edges of said back plate.

4. A device as described in claim 3 wherein said wedging means each comprises a metal rod extending substantially the length of said shoe.

5. In an ironing machine shoe having an electric resistance heating element, in combination, a metallic sole plate, longitudinal retroverted portions extending along either side of said sole plate for substantially the entire length thereof and forming overhanging lips, a pad of heat in-

sulating material disposed over said heating element, a back plate comprising a shallow trough of substantially the same length as said shoe, said trough being adapted to cover said heating element and said pad, a longitudinal marginal flange portion extending along each side of said trough and adapted to slide under and engage said lips, and means for wedging said flanges beneath said lips to force said flanges into contact with said sole plate and to force said trough portion against said pad.

6. A device as described in claim 5 wherein said trough portion is provided with inwardly projecting portions located over said electric resistance unit.

7. In an ironing machine shoe having a sole plate and an electric heating unit of the type comprising a pair of electric resistance elements mounted parallel to each other between two sheets of mica, said resistance elements extending longitudinally of said heating unit, and said heating unit being positioned in contact with the back of said sole plate, in combination, a heat insulating pad substantially covering said heating unit, a back member, a pair of depressions in said back member extending longitudinally thereof and arranged to register substantially over said resistance elements, and means for securing said back member to said sole plate so as to distort said back member whereby said back member depressions concentrate pressure on said insulating pad over substantially only the area of said depressions to force said heating unit into intimate contact with said sole plate substantially over the areas within which are contained the resistance elements.

8. In an ironing machine shoe having an electric heating unit comprising resistance elements encased in a dielectric, in combination, a metallic sole plate, the longitudinal edges thereof being retroverted to form U-shaped pockets, a sheet metal back plate extending substantially the length of said sole plate and shaped to form a chamber for receiving said heating element therein, a plurality of inwardly projecting portions formed integrally in said back plate and located so as to register over said resistance elements when said shoe is assembled, flanges extending along the longitudinal edges of said back plate, said flanges being adapted to extend into and engage with said U-shaped pockets, and wedging means adapted to be forced into said pockets over the flanges of said back plate whereby said back plate is forced downwardly along the edges thereof and is bowed so as to cause said inwardly projecting portions to exert resilient pressure over the resistance elements to bring the heating unit into intimate contact with said sole plate.

9. In an ironing machine shoe having an electric heating unit comprising resistance elements encased in a dielectric, in combination, a metallic sole plate, the longitudinal edges thereof being retroverted to form U-shaped pockets, a sheet metal back plate extending substantially the length of said sole plate and shaped to form a chamber for receiving said heating element therein, a plurality of inwardly projecting portions formed integrally in said back plate and located so as to register over said resistance elements when said shoe is assembled, flanges extending along the longitudinal edges of said back plate, said flanges being adapted to extend into and engage with said U-shaped pockets, and removable combined back plate anchoring and

flexing means adjacent each longitudinal edge of said back plate and interposed between the outer face of the back plate and the adjacent over-hanging edge of the sole plate to releasably anchor the back plate to the sole plate and in continuous plate flexing pressure contact with the outer face of the back plate adjacent said over-hanging edges of the sole plate to flex the back plate transversely toward the sole plate to exert resilient pressure over the resistance elements by means of the inwardly projecting portions to create a heat transfer path of low resistance between said resistance elements and said sole plate.

10. In an ironing machine shoe having a sole plate and an electric heating unit comprising a plurality of resistance elements encased in a dielectric and extending longitudinally of said sole plate, said heating unit being positioned in contact with the back of said sole plate, in combination, a pressure plate for exerting pressure on

5 said heating unit over substantially the area included by said resistance elements, said plate comprising a longitudinally disposed chamber portion within which is positioned said heating unit, a plurality of inward depressions in said chamber portion arranged longitudinally thereof to register over said resistance elements, marginal portions, one extending along each longitudinal side of said chamber portion, said marginal portions being spaced away from said sole plate when said shoe is assembled and before fastening said pressure plate to said sole plate, and means for drawing said marginal portions toward said sole plate along the length of said shoe and removably fastening said pressure plate to said sole plate whereby said pressure plate is flexed laterally to exert a resilient pressure through said inward depressions on said heating unit over substantially the area of said heating unit included by said resistance elements.
